UNITED STATES PATENT OFFICE.

JOEL R. COOK, OF CLEVELAND, OHIO, ASSIGNOR, BY MESNE ASSIGNMENTS, TO WESTINGHOUSE ELECTRIC & MANUFACTURING COMPANY, A CORPORATION OF PENNSYLVANIA.

THERMOSTATIC CONTROL FOR ELECTRIC SWITCHES.

Application filed July 3, 1924. Serial No. 723,889.

This invention is concerned with the control of electric switches and has for its object the provision of a simple, compact and efficient thermostatic control in an electric circuit breaker.

A more specific object of my invention is the provision of an electric current-carrying bimetallic thermostatic element to comprise a mechanical control for an electrical switch and to constitute, permanently, a part of the circuit controlled by the switch.

Other objects of my invention will be hereinafter set forth in the following description referring to the accompanying drawings illustrating a preferred embodiment thereof. The essential characteristics are summarized in the claims.

In the drawings Fig. 1 is a plan view of a simple switch mechanism incorporating my thermostatic control; Fig. 2 is an enlarged side elevation of a thermostatic element; and Fig. 3 is a cross-sectional view taken through the base of the switch along the line 3—3 of Fig. 1 and illustrating a convenient mounting for the thermostatic element.

My invention, as shown in the drawings, may be embodied in a switch or circuit breaker in a very simple manner to normally maintain the contacts of the switch closed by opposing the action of a switch-opening means, usually a spring. In Fig. 1, a switch or circuit breaker is shown of the general type disclosed and claimed in my prior application pertaining to an electric switch filed Sept. 18, 1922, Ser. No. 588,755. For convenience in illustration, the switch may comprise a base 6 formed of suitable insulating material and upon which are mounted stationary contacts 7 and 8 which may comprise L-shaped members having outwardly extending contacting portions 9 and 10, respectively. The contacting surfaces thereof may be radially disposed whereby movable contact members 11 and 12 may be mounted to swing about a pivotal center 13. The movable members 11 and 12 may be mounted upon the free ends of a resilient bridging member 14 insulatingly secured at its center to a revoluble bridge-supporting member 16. The free arms 14^a and 14^b of the bridging member may thus comprise a resilient supporting means for the

movable contacts 11 and 12, respectively, to permit proper contact between the current-conducting members 9, 11, 10 and 12, respectively.

The supporting member 16 may be mounted upon a staff 18 pivotally supported by the base 6, the shaft being actuated in a well known manner by a handle or knob, not shown. To resiliently bias the member 16 a spring member 20 may surround a hub portion 16^a of the bridge-supporting member 16 with one end secured to the staff and the other end in engagement with an outwardly extending lug on the supporting member 16. The spring 20 may be tensioned by the manual turning of the staff 18 to bring the contacts 11 and 12 into closing relationship with the stationary contacts 9 and 10 respectively. The member 16 may be maintained in such position by the action of a deflectable current carrying bi-metallic thermostatic member 25, which may be mounted to comprise a cantilever with the free end 26 thereof serving to engage a projecting member 27 insulatingly mounted upon the projecting lug 22 of the member 16.

The thermostatic member 25, as shown in Fig. 2, may be formed of a bi-metallic sheet to comprise a loop of U-shape, as shown, with the ends 27' and 28 of the ends of the loop secured to supporting members 30 and 31, respectively. The latter members may be of an L-shape, as shown in Fig. 3, with a suitable insulating member 34 disposed therebetween, whereby the looped thermostatic member may comprise a permanent part of the circuit controlled by the separable contacts. The mounting of the thermostatic member, as shown in Fig. 3, is accordingly such that lead wire 35 may be connected to a terminal-securing bolt 42 which serves to clamp the supporting members of the thermostatic element to the insulating base 6 with a nut 38 serving as a tightening or clamping medium. The current would thus come into the switch through the line 35 through the securing bolt 42, through the member 31, traverse the lower leg of the thermostatic element 25, as indicated by the arrow in Figs. 2 and 3, and return along the upper leg. The current would then pass to the connected terminal support 30 and thence through the bolt 36 and to a line 39

connected to a securing bolt 41, which clamps the stationary contact member 8 to the base, and thereafter through the bridge member 14 to the stationary contact 7 and then out through the line 40 connected to a securing bolt 44.

The thermostat 25 may be formed from a bimetal sheet in a well known manner whereby the inner side may have a greater coefficient of expansion than the outer side to cause the thermostat to curl or deflect outwardly. Hence, when an overload condition exists in the line 35 and 40, the resistance of the bi-metal comprising the thermostatic element will cause the formation of sufficient heat in the element to effect its outward deflection to release the detent member 27 and permit the spring member 20 to swing the contact-supporting member 16 to open position, whereupon the thermostatic element 25 will immediately cool and assume its normal position and, upon resetting of the contact supporting member 16, the member 27 will wipe over the inner face of the element, springing it outwardly until the end thereof is passed by the detent member 27, whereupon it will spring inwardly and retain the element of the switch, as shown in Fig. 1, until another over-load condition occurs in the line.

It will be seen that the shape of the thermostatic element is such that current traverses the length thereof in two directions and that there is no electrical connection between the element and movable parts of the switch where undue arcing or sparking might occur. The element remains connected in the circuit regardless of whether the switch is open or closed and is of such simple form that the resistance and corresponding deflecting characteristics may be accurately predetermined, permitting the element to be manufactured in large quantities without necessitating the calibration of each element to determine its resistance and deflective characteristics.

I claim—

1. In an electric switch the combination of a bimetallic current carrying thermostatic member and a mounting therefor, said member being substantially U-shaped and the mounting comprising a base member and a pair of superposed current carrying members electrically insulated from each other and disposed at one side of the U but in planes parallel therewith, one member being connected to and supporting one leg and the other the other leg of the thermostatic member whereby the thermostatic member will 60 extend along the base.

2. In an electric switch the combination of stationary contact members, swingable contact members adapted to bridge the sta-

tionary members to close a line, a swingable contact supporting means therefor including an abutment, a spring tending to maintain the supporting means with the contact members in a line opening position and a bimetallic current carrying thermostatic member comprising a permanent part of the line and mounted to form a cantilever strut with the free end acting as a detent against the abutment substantially at right angles with relation to the abutting surface thereof to oppose the swinging movement of the supporting means.

3. In an electric switch, the combination of a bimetallic current-carrying thermostatic member and a mounting therefor, said member being loop shaped and the mounting comprising a base member and two current-carrying members each being connected to a respective end of the loop member and being in superposed relation in planes parallel to the general plane of the loop whereby the thermostatic member may be suspended in offset substantially parallel relation to the base.

4. In an electric switch, the combination of a bimetallic current-carrying thermostatic member mounted to comprise a cantilever, said member being substantially U-shaped and the mounting comprising a pair of L-shaped current-carrying members electrically insulated from each other and in superposed relation, each member supporting a leg of the thermostatic member in offset but substantially parallel relation to the base.

5. In combination, a thermostatic element forming part of the circuit of an electric switch comprising a looped bimetallic member having legs separated and lying in vertical alignment with reference to a common base, a pair of metallic supporting members individually secured to said legs at their ends and in overlying relation but insulated from each other, and means passing through such supporting members and adapted to serve as an electric conductor lead for one of them and to clamp both said members to such base.

6. In an electric switch, the combination of a base, a looped bimetallic member connected to permanently comprise a part of the switch circuit, means to hold the member with the legs of the loop in vertical alignment with reference to the base and serving to establish connections to the switch circuit whereby the bimetallic member is constrained to curl in a plane parallel to the base for the purpose of holding and releasing a switch contact control member oscillatable on a shaft extending at right angles to the base.

Intestimony whereof, I hereunto affix my signature.

JOEL R. COOK.
